STEAM GENERATOR AND WATER HEATER

Filed May 16, 1928

FIG. I.

INVENTOR
Thomas Clarkow

By Watson, Cort,
Morse & Grindle 1875

UNITED STATES PATENT OFFICE

THOMAS CLARKSON, OF LONDON, ENGLAND

STEAM GENERATOR AND WATER HEATER

Application filed May 16, 1928, Serial No. 278,111, and in Great Britain May 30, 1927.

This invention relates to steam generators or water heaters of the type comprising two concentrically arranged substantially cylindrical members of different diameters each 5 closed at its lower end while the upper ends are connected together so that a steam and water space is formed between the two members of which the inner one carries a series of thimbles projecting radially into a central 10 gas space.

Where heat is supplied to a generator or water heater of this type by means of a flame as from a burner directed downwardly into the central gas space, the excessive heat 15 which is then directed against the centre portion of the lower end of the inner member of the generator tends to cause damage to this part. This is due to the fact that it has been customary hitherto to form as flatly rounded 20 or with a curvature of large radius the closed lower end of this inner member. Further, where the generator is heated by a burner arranged as indicated, it is desirable to provide means whereby undue heating of the upper 25 end of the generator casing may be avoided. The object of the present invention is to effect certain modifications in the structure of this type of generator and in the disposition of the burner and arrangement of 30 the air supply thereto so as to obviate the risk of damage to the lower part of the generator while providing means for cooling the upper part of the generator casing.

According to the present invention the 35 closed lower end of the inner member of the steam generator or water heater is formed substantially conical the angle of the apex of the cone being conveniently not more than 120°. A baffle member is provided in the 40 water space between the concentric inner and outer generator members this baffle member being formed approximately cylindrical as to its upper part with an inwardly directed and substantially conical base having a central 45 opening therein. This baffle member is disposed so as to lie between and be spaced apart from the inner and outer steam generator members so that the water space, not only in the vertical annular portion of the generator, but also at the bottom thereof, is di-

vided by the baffle member in such a manner that circulation of the water will tend to be induced downwards outside the baffle and towards the centre of the bottom of the generator and thence upwards inside the baffle 55 over the conical lower end of the inner generator member and the upper part of this member which carries the thimbles. By this means such a circulation of water is caused to take place over the lower end of the inner 60 generator member as will obviate the risk of the centre portion of this lower end being damaged by the heat impinging thereon.

The diameter of the cylindrical portion 65 of the baffle is appreciably less than the internal diameter of the outer shell or member of the generator but substantially greater than the outer diameter of the inner generator member. The lower portion of the baffle is given a conical formation substantially conforming to that of the lower end of the inner generator member. The opening in the centre of the conical lower end of the baffle is of suitable dimensions and the spacing between this part and the conical lower end of 70 the inner generator member is such as to allow of free flow and the desired upward scouring circulation of the water over the conical surface of the inner end of the generator and between this part and the baffle. 75

Refractory material such as firebrick preferably in a broken state may be disposed in the centre of the conical lower end of the inner generator member so that the heat from the downwardly directed flame will impinge 80 on to this material.

The burner is preferably arranged so as to direct the flame into the interior of the inner generator member through a tubular inlet 85 passage which is so disposed in the upper part of the generator that it is surrounded by an annular space which may be regarded as forming a chamber through which the hot gases after flowing over the generator thimbles, pass upwards to a laterally arranged 90 gas outlet at the upper end of the generator casing. This tubular gas inlet or flame passage is preferably provided in its upper part with a conical perforated member immediately 95 below which is arranged a firebrick or like 100

lining. The liquid fuel burner is carried by a plate mounted at the upper end of the generator so that the flame is directed downwards through the conical perforated member and the firebrick lined portion of the tubular flame passage into the central gas space of the generator, the tubular flame passage preferably being extended downwards below the firebrick lined portion into the space between the thimble tubes.

19. The invention may be carried into practice in various ways but one construction according to this invention is illustrated by way of example in the accompanying drawings, in which

15. Figure 1 is a sectional elevation, and
Figure 2 is a plan.

In the construction illustrated the generator or water heater comprises two concentric tubular generator members A and B of different diameters each closed at its lower end and open at its upper end, the upper ends being connected together for example by a separate annular member C so as to enclose between the generator members a space A¹ for water or water and steam. The lower closed end A² of the outer generator member A, which in the construction shown is formed separately from and secured to the tubular wall of this member but may if desired be formed integral with such tubular wall, has a substantially spherical surface. The lower closed end B¹ of the inner generator member B which may also be formed either integral with or, as shown, separately from the tubular wall of such member, is, on the other hand, formed substantially conical, the angle at the apex of the cone being as shown not more than 120°. The apex of the cone is conveniently rounded off as shown at B² and may be provided internally with a filling of refractory material B³ such as firebrick, preferably in a broken state.

45. A series of closed-ended water tubes D extend radially inwards from the wall of the inner generator member B, a portion B⁴ of the tubular wall of this member towards its upper end being unprovided with thimble tubes and somewhat reduced in diameter.

50. Arranged in the annular water space A¹ between the inner and outer generator members and having a diameter less than the internal diameter of the outer generator member, but greater than the external diameter 55 of the inner generator member, is a baffle member E E¹, this baffle member being formed approximately cylindrical as to its upper part E with an inwardly directed and substantially conical base E¹ having a central opening E² therein. The baffle member E E¹ is conveniently supported on studs E³ from the outer generator member A and is disposed as shown so as to lie between and be spaced apart from the inner and outer 65 generator members so that the water space,

not only in the vertical annular portion of the generator but also at the bottom thereof, is divided by the baffle member E E¹ in such a manner that circulation of the water will tend to be induced downwards outside the baffle and towards the centre of the bottom A² of the generator and thence through the hole E² and upwards over the conical lower end B¹ of the inner generator member and the upper part of this member which carries the thimble tubes D. Further, a deflecting member B⁵ may be provided on the lower end A² of the outer generator member A to assist the flow of water into the opening E² in the baffle E E¹. Secured to the annular member 70 C connecting the upper ends of the inner and outer generator members is a structure F hereinafter termed a burner case. This case F is so formed as to close in the upper portion of the gas space G of the generator and to 75 form in effect an annular chamber G¹ constituting an extension of such gas space into which the gases flow after passing out of the inner generator member proper and before flowing to an outlet pipe G³ leading from the 80 annular chamber G¹.

85. The outlet G³ conveniently leads laterally from the chamber G¹ and the burner case F conveniently comprises in addition to the chamber G an outer chamber H surrounding the chamber G¹ except where the outlet G³ leads therefrom and also extending over the top of the chamber G¹, the chamber H communicating with the atmosphere through a suitable passage H¹ which may be provided 90 with a fan or blower.

95. The upper wall of the chamber H¹ is constituted partially or wholly by a plate J in the centre of which is carried a fuel sprayer K arranged substantially coaxially with the 100 generator and preferably of the type employing an atomizing blast of air or steam.

105. The burning gases and products of combustion from the sprayer are directed 110 through a flame tube L L¹ into the interior of the inner generator member B, the upper portion L of the flame tube constituting the inner wall of each of the annular chambers G and G¹. The upper portion L of the flame tube is of somewhat larger diameter than the lower portion L¹ and has mounted within it 115 a hollow perforated cylinder M of somewhat less external diameter than the internal diameter of this part of the flame tube. Disposed within the cylinder M is a conical perforated member M¹ disposed coaxially with the sprayer and arranged with its smaller end adjacent thereto, this conical member bearing at its lower end a refractory lining M² as shown and being held in place by the 120 tubular member M. The external diameter of the refractory lining M² is somewhat less than the internal diameter of the surrounding portion of the flame tube so that a small air space M³ surrounds the refractory lining, 125 130

this lining being provided with ribs or serrations M^4 at its lower end as shown so as to permit air to pass laterally from the space M^3 into the lower portion L^1 of the flame tube.

5 It will be seen that with the construction illustrated, since the perforated cylinder M is of less diameter than the upper portion L of the flame tube, air can flow from the interior of the casing M into the annular space between the cylinder M and the flame tube L . This air can flow downwards through the space M^3 surrounding the refractory lining M^2 and thence radially into the lower end L^1 10 of the flame tube whereby the upper portion L of the flame tube is insulated by a jacket of cool air from the intense heat of the refractory lining M^2 . The extreme lower end of the flame tube is conveniently tapered some 15 what as indicated at L^2 .

The operation of the burner described above is as follows. The air for combustion enters through the inlet passage H^1 in the chamber H either directly from the atmosphere or under pressure from a blower or fan and in so doing will pass over the outer wall of the chamber G^1 and thus will become heated since the hot gases from the generator pass through the chamber G^1 on their way to 20 the gas outlet G^3 . Some of this air will enter the perforated conical member M^1 at its upper end adjacent to the sprayer and will mingle with the fuel delivered thereby and serve for the combustion of such fuel 25 while the remaining air flows into the space between this conical member and the perforated cylinder M and thence passes partly through the perforations in the conical member M^1 and partly through the perforations 30 in the cylindrical member M . The air passing through the perforations in the conical member M^1 assists in the combustion of the fuel delivered by the sprayer K while that passing through the perforations in the cylindrical member M passes downwards through 35 the space between this member and the flame tube L into the space M^3 between the flame tube and the refractory lining M^2 whence it passes out through the radial openings into 40 the lower end L^1 of the flame tube.

The hot gases from the burner flow downwards through the flame tube into the lower end of the inner generator member B and after flowing upwards around and over the 45 thimble tubes D will pass around the upper portion L of the flame tube into the chamber G^1 whence they pass to the gas outlet G^3 .

The heat from the gases delivered by the burner is transmitted through the thimble tubes D and the wall of the inner generator member B to the water and will cause the water within the baffle E to flow upwards. The upward flow thus caused within the cylindrical portion of the baffle E , assisted 50 by the conicity of the closed lower end B^1

of the inner generator member B , will tend to produce a rapid combined radial and upward flow of water between the conical lower portion E^1 of the baffle E and the conical end B^1 of the inner generator member B thus 70 tending to maintain this end cooled and to prevent the formation of stationary steam bubbles thereon.

The generator is conveniently provided with an inlet pipe N for feed water and a 75 perforated collecting pipe O for steam.

It is to be understood that the constructional details may be varied within wide limits without departing from this invention according to the purpose for which the generator or water heater is intended and the type of burner which is to be employed. Further, although the invention has been described with particular reference to generators or water heaters employing liquid or gaseous 80 fuel burners, it may also be applied to generators or water heaters in which the hot gases are derived from some other source wherein the temperature of these gases is such as to tend to cause over-heating of the lower closed 85 end of the inner generator member.

What I claim as my invention and desire to secure by Letters Patent is:—

1. A water heater including in combination a cylindrical outer shell disposed vertically and having the lower end thereof closed, a tubular inner shell whose external diameter is less than the internal diameter of the outer shell and having a conical closure at its lower end, the two shells being disposed concentrically with a steam and water space between their sides and lower ends, an annular member connecting the upper ends of these shells and closing in the steam and water space, a series of thimble tubes projecting 95 radially inwards from the wall of the inner shell into a central heating space, a downwardly directed burner mounted opposite to the open end of the inner shell and delivering hot gases into this heating space, a sheet 100 metal baffle member comprising a tubular main part and a conical end portion with a central opening therein this baffle member being disposed in the steam and water space 105 where it lies intermediate between the adjacent external and internal side and end surfaces of the inner and outer shells, the baffle tending to cause water to circulate downwardly between the baffle and the outer shell through the opening in the lower end of the 110 baffle member and upwards between this member and the inner shell.

2. A water heater including in combination a cylindrical outer shell disposed vertically and having the lower end thereof closed, a tubular inner shell whose external diameter is less than the internal diameter of the outer shell and having a conical closure at its lower end the angle at the apex of which is not more than 120° , the two shells being disposed 115 120 125 130

concentrically with a steam and water space between their sides and lower ends, an annular member connecting the upper ends of these shells and closing in the steam and water space, a series of thimble tubes projecting radially inwards from the wall of the inner shell into a central heating space, a downwardly directed burner mounted opposite to the open end of the inner shell and delivering hot gases into this heating space, a sheet metal baffle member comprising a tubular main part and a conical end portion with a central opening therein, this baffle member being disposed in the steam and water space where it lies intermediate between the adjacent external and internal side and end surfaces of the inner and outer shells, the baffle tending to cause water to circulate downwardly between the baffle and the outer shell, through the opening in the lower end of the baffle member and upwards between this member and the inner shell.

3. A water heater including in combination a cylindrical outer shell disposed vertically and having the lower end thereof closed, a tubular inner shell whose external diameter is less than the internal diameter of the outer shell and having a conical closure at its lower end the angle at the apex of which is not more than 120° , the two shells being disposed concentrically with a steam and water space between their sides and lower ends, an annular member connecting the upper ends of these two shells and closing in the steam and water space, a series of thimble tubes projecting radially inwards from the wall of the inner shell into the central heating space and a downwardly directed burner mounted opposite to the open end of the inner shell and delivering hot gases into this heating space.

4. A water heater including in combination a cylindrical outer shell disposed vertically and having the lower end thereof closed, a tubular inner shell whose external diameter is less than the internal diameter of the outer shell and having a conical closure at its lower end, the two shells being disposed concentrically with a steam and water space between their sides and lower ends, an annular member connecting the upper ends of these shells and closing in the steam and water space, a series of thimble tubes projecting radially inwards from the wall of the inner shell into a central heating space, a downwardly directed burner mounted opposite to the open end of the inner shell and delivering hot gases into this heating space, a flame tube into the upper end of which the hot gases from the burner pass, this flame tube being disposed concentrically with the inner shell between the closed inner ends of the thimble tubes and of such length that the hot gases after flowing through the flame tube pass from the lower end thereof into the heating space adjacent to

its lower end and only come in contact with the thimble tubes during their upward motion through the space surrounding the flame tube as they pass towards a gas outlet at the upper end of this space, a tapered and perforated tubular member in the upper portion of the flame tube arranged with its smaller end adjacent to the burner, a refractory lining for the portion of the flame tube immediately below this perforated member, means for supplying air to the upper end of the flame tube and the space surrounding the perforated tubular member, means for permitting the escape of hot gases from the space surrounding the upper end of the flame tube, a sheet metal baffle member comprising a tubular main part and a conical end portion with a central opening therein, this baffle member being disposed in the steam and water space where it lies intermediate between the adjacent external and internal side and end surfaces of the inner and outer shells, the baffle tending to cause water to circulate downwardly between the baffle and the outer shell, through the opening in the lower end of the baffle member and upwards between this member and the inner shell.

5. In a water heater, the combination with a substantially vertical container for water provided with a heating space interiorly thereof, of a burner arranged to deliver hot gases downwardly into the said heating space, a flame tube into the upper end of which the hot gases from the burner pass, this flame tube being disposed within the heating space and of such length that the hot gases after flowing through the flame tube pass from the lower end thereof into the heating space adjacent to its lower end and only come in contact with the container walls during their upward motion through the space surrounding the flame tube, an annular chamber surrounding the upper end of the flame tube and into which the hot gases flow before issuing from the heating space, and an air inlet passage surrounding this annular chamber and serving to deliver air to the upper end of the flame tube.

6. In a water heater, the combination with a substantially vertical container for water provided with a heating space interiorly thereof, of a burner arranged to deliver hot gases downwardly into the said heating space, a flame tube into the upper end of which the hot gases from the burner pass, this flame tube being disposed within the heating space and of such length that the hot gases after flowing through the flame tube pass from the lower end thereof into the heating space adjacent to its lower end and only come in contact with the container walls during their upward motion through the space surrounding the flame tube, a tapered and perforated tubular member in the upper portion of the flame tube arranged with its smaller end adjacent to

the burner, a refractory lining for the portion of the flame tube immediately below this perforated member, an annular chamber into which the hot gases pass after flowing upwards through the space surrounding the flame tube, an outlet from this chamber, and an air inlet passage surrounding this annular chamber and serving to deliver air to the upper end of the flame tube and the space surrounding the tubular perforated member.

In testimony whereof I have signed my name to this specification.

THOMAS CLARKSON.
